CONCRETE INSERT

Filed Nov. 10, 1926

Inventor:
Thomas K. Cummins,
By John Miller Refiled
City.

Patented July 23, 1929.

1,722,242

UNITED STATES PATENT OFFICE.

THOMAS K. CUMMINS, OF ST. PAUL, MINNESOTA, ASSIGNOR TO NORTHERN MALLEABLE IRON COMPANY, OF ST. PAUL, MINNESOTA, A CORPORATION OF MINNESOTA.

CONCRETE INSERT.

Application filed November 10, 1926. Serial No. 147,596.

My invention relates to concrete inserts, such as are intended to be set in concrete floors, walls, ceilings, and the like to facilitate the attachment of various articles or devices.

5 One of the objects of the invention is to provide a simple, practical and advantageous construction or form of concrete insert.

Another object of the invention is to arrange for the ready attachment of the bolt or 10 rod or pipe or other device in a simple and easy manner.

Another object of the invention is to permit the bolt or rod or pipe after connection with the insert, to be readily adjusted to permit connection with other parts or devices 15 and particularly to permit it to be turned or rotated so as to make screw connection with another threaded part, without unscrewing the nut or threaded member by which the bolt 20 or rod or pipe is connected with the insert.

Another object of the invention is to arrange for the use of reenforcing rods for assisting in holding the insert in position in the concrete if desired.

25 Other objects of the invention will appear and be pointed out hereinafter.

In an application filed by me, Serial No. 124,579, filed July 24th, 1926, for concrete insert, I have shown, described and claimed a 30 concrete insert having certain of the features of construction and operation of the device herein set forth.

In the accompanying drawings:

35 Fig. 1 is a view showing a concrete insert embodying my invention and also a portion of the wall or ceiling in which the same is imbedded, and also showing the temporary or false work used in connection with the wall or ceiling.

40 Fig. 2 is a longitudinal section taken on line 2-2 of Fig. 1.

Fig. 3 is a bottom view of the device looking upward.

45 Figs. 4 and 5 are cross sections taken on lines 4-4 and 5-5 respectively in Fig. 1.

In the drawings I show a concrete insert 1 preferably made of metal and so designed that it may be cast. This insert is shown imbedded in concrete material A, the false work 50 B being also shown.

The insert 1 is of generally elongated form having an upper chamber or recess 2 and a lower chamber or recess 3. The top 4 preferably projects laterally beyond the side and 55 end walls so as to form an anchor or abut-

ment arrangement for assisting in holding and securing the device in position in the concrete.

The upper chamber or recess 2 is to receive the upper end of the bolt or pipe or rod to 60 be supported by the device, a bolt 5 being shown in the drawings for illustrating the method of using the device. The upper end of this bolt 5 or bar or pipe or other element supported by the insert would project into 65 the recess 2 more or less according to the extent to which the bolt or pipe entered the device and vertical adjustment of the same would be permitted by this chamber 2.

A nut 6 for the bolt 5 is shown in the lower 70 chamber 3. This chamber 3 is preferably wider than the upper chamber 2, with shoulders 7-7 preferably formed on the side walls of the device for preventing the nut 6 from entering the chamber 2 while permitting the 75 end of the bolt, rod or pipe to enter said chamber 2. The bottom 8 of the device is provided with an elongated slot 9 communicating with the lower chamber 3. This slot 9 is sufficiently wide to readily accommodate the bolt 5 or 80 other similar element and is also preferably of such width as to permit the nut 6 to be readily inserted or pushed through the slot 9 into the lower chamber 3 and the latter is of such 85 height and size as to allow the nut 6 to be turned or tilted as shown in Fig. 4 after said nut has been pushed through the slot 9 as shown in said figure.

The lower chamber 3 also preferably has one portion as for example the portion 10 90 which is relatively narrow or contracted, being only slightly wider than the width of the nut 6, as shown in Fig. 2, so that said nut 6 cannot be turned or rotated in said chamber portion 10. Said chamber 3, however, has 95 preferably another portion as 11 which is wider than the portion 10 and of such width as to permit nut 6 to be turned or rotated in said portion 11 as shown in Fig. 2, nut 6 being shown in dotted lines in said figure with in the portion 11 in a turned position, showing it may turn completely around in said portion 11. Said portions 10 and 11 may be variously located but are by preference arranged at the opposite ends of the chamber 3 100 and at more or less opposite ends of the device as a whole.

One end 12 of the device is preferably inclined to provide an inclined chamber 13 in which the bolt 5 or similar element may be 110

placed so as to give it an inclination and thereby permit angular adjustment of bolt 5 or like element.

By such arrangement the device may be 5 operated as follows:

The nut 6 may first be pushed through slot 9 into chamber 3 and then turned so as to place it in a flat or horizontal position and then the bolt 5 or like element may have its 10 threaded end pushed through slot 9 and screwed into nut 6. In some cases the article or device to be attached to bolt 5 or like element may then be fastened to or hung upon said member 5 in the manner desired with the 15 nut 6 confined in portion 10 of chamber 3 as shown in full lines in Fig. 2. In other cases angular adjustment of bolt 5 or similar part may be desired in which case said bolt 5 may be arranged as shown in Fig. 1. In other 20 cases, however, it may be desired to turn bolt 5 or similar element after it has been arranged in or connected to the insert, in order that some other threaded article or part may be secured by screwing to the lower end of 25 bolt 5 or pipe or bar secured to the insert as described in connection with bolt 5. In these other cases it is apparent that a turning of bolt 5 or pipe or bar with the nut 6 held against rotation, might result in said member 30 5 being unscrewed out of the nut 6, thereby disconnecting member 5 from nut 6 and destroying the connection so that the whole arrangement would fail of its purpose. In order to avoid this where so desired to turn 35 member 5 for further screw threaded connection, said member 5 may be moved to the left referring to Figs. 1, 2, and 3, so that nut 6 will move out of chamber portion 10 into chamber portion 11 and when in this position element 5 or the like may be turned or 40 rotated to any desired extent so that a screw threaded connection may be made with another part or article or hanging as desired. After this threaded connection is made the element 5 may if desired be turned so that 45 nut 6 may reenter channel or recess 10 and element 5 may then be moved to cause such entry of nut 6 into channel 10 and the device may be left in this condition in which element 5 will 50 be firmly and securely held in position and against rotation with screw threaded connection at each end.

It will be seen that while the nut or holding element 6 is in its chamber 3 with the supporting member 5 attached, said member 5 55 may be moved back and forth longitudinally of the device to any desired extent in order to secure any adjustment of the holding element 5 to any position in which it is desired to place it, according to the requirements of the device to be supported. Furthermore, in any such longitudinal position the member 5 60 may be arranged at any angularity desired for the accommodation of the device to be supported or the position of this device 1 in the

concrete or other material in which it is to be set, and this longitudinal and angular adjustability of member 5 is not interfered with in the least by the enlargement 11 of chamber 10, nor is there any likelihood of the nut or 70 holding element 6 becoming displaced or working loose by reason of such enlargement 11. Furthermore, if by reason of excessive loading or carelessness in starting member 5 into element 6 or for other reason the screw 75 threads are spoiled or stripped, element 6 may be removed and a new one inserted in its place.

As a preferred arrangement a loop 14 is secured to the top 4 as by casting it integral 80 with the rest of the device. This loop 14 has an aperture 15 to accommodate reenforcing rods where the weight to be supported is such as to make it unsafe to depend entirely upon the adherence to the concrete. 85

Also as a preferred arrangement the bottom 8 is provided with side projections 16 and 17 having recesses or notches 18 and 19 respectively to accommodate nails or wires 20 for securing the device to the temporary or 90 false work B.

It will be understood that changes and modifications may be made without departing from the spirit of the invention. 95

What I claim is:

1. A device of the class specified having a longitudinally extending chamber one end of which is relatively narrow to prevent turning of a holding element and the other end of which in the same horizontal plane is relatively wide to permit turning of said element. 100

2. A device of the class specified having upper and lower longitudinally extending chambers whereof the upper chamber is relatively small and the lower chamber relatively wide, the bottom of the device being provided with a slot communicating with the lower chamber and said slot and the lower chamber being of such size as to permit a holding element to be pushed through the slot and into 110 the lower chamber and then turned flatwise, the lower chamber having one of its ends made relatively narrow to receive said holding element and prevent turning of same and having its other end made relatively wide to receive 115 said holding element and permit turning of the same.

3. A device of the class specified having upper and lower longitudinally extending chambers whereof the upper chamber is relatively small and the lower chamber relatively wide, the bottom of the device being provided with a slot communicating with the lower chamber and said slot and the lower chamber being of such size as to permit a holding element to be pushed through the slot and into the lower chamber and then turned flatwise, the lower chamber having one of its ends made relatively narrow to receive said holding element and prevent turning of same and having 125 130

its other end made relatively wide to receive said holding element and permit turning of the same, the end of said device opposite the widened end of said lower chamber being provided with an inclined end wall forming an inclined chamber for permitting angular adjustment of the member supported by said holding element.

4. A device of the class specified having a body providing a longitudinally extending chamber, said body also having a bottom wall provided with longitudinally extending slot communicating with said chamber, said slot being of such width as to permit the insertion through it of a holding element to be confined in said chamber and said chamber having a side enlarged portion adapted to permit the turning in it of said holding element.

5. A device of the class specified having a body providing a longitudinally extending chamber, said body also having a bottom wall provided with longitudinally extending slot communicating with said chamber, said slot being of such width as to permit the insertion through it of a holding element to be confined in said chamber when it is in an inoperative position and said chamber having a side enlarged portion adapted to permit the turning in it of said holding element when it is in its operative position, said chamber being also adapted to permit said holding element to be turned from a vertical inserting position to a flatwise holding position after said element is inserted through said slot.

6. A device of the class specified having a body providing a longitudinally extending chamber, said body also having a bottom wall provided with longitudinally extending slot communicating with said chamber, said slot being of such width as to permit the insertion through it of a holding element to be con-

fined in said chamber and said chamber having an enlarged portion adapted to permit the turning in it of said holding element, said chamber being also adapted to permit said holding element to be turned from a vertical inserting position to a flatwise holding position after said element is inserted through said slot, said chamber having an angular portion adapted to permit the angular positioning of the member engaging and supported by said holding element.

7. A device of the class specified provided with a chamber for a confined holding element, one portion of said chamber being relatively small to prevent turning of said element and another portion in the same horizontal plane and at one side of the first mentioned portion being relatively large to permit turning of the same.

8. A device of the class specified provided with a longitudinally extending chamber having a relatively narrow portion to prevent turning of a confined holding element and also having another portion at one side of the first mentioned portion and in the same horizontal plane sufficiently wide to permit turning of said element.

9. A device of the class specified having upper and lower chambers whereof the upper chamber is relatively small and whereof the lower chamber is relatively large, the lower chamber having a relatively narrow portion to receive a holding element but to prevent turning of the same and also having a relatively wide portion at one side of the first mentioned portion and in the same horizontal plane to receive said holding element and permit turning of the same.

In witness whereof, I hereunto subscribe my name this 19 day of October A. D., 1926.

THOMAS K. CUMMINS.
